CLAIM

The ornamental design for a pistol magazine, as shown and described.

DESCRIPTION

FIG. 1 is a right-side, front, and top perspective view of a pistol magazine showing our new design with an unclaimed base plate including a grip extension;

FIG. 2 is left-side, front, and top perspective view thereof;

FIG. 3 is a right-side and rear perspective view thereof;

FIG. 4 is a left-side and rear perspective view thereof;

FIG. 5 is a right-side elevational view thereof;

FIG. 6 is a left-side elevational view thereof;

FIG. 7 is a front elevational view thereof;

FIG. 8 is a rear elevational view thereof;

FIG. 9 is a top plan view thereof; and

FIG. 10 is a bottom plan view thereof.

FIG. 11 is a right-side, front, and top perspective view of a pistol magazine shown with an unclaimed flush base plate;

FIG. 12 is left-side, front, and top perspective view thereof;

FIG. 13 is a right-side and rear perspective view thereof;

FIG. 14 is a left-side and rear perspective view thereof;

FIG. 15 is a right-side elevational view thereof;

FIG. 16 is a left-side elevational view thereof;

FIG. 17 is a front elevational view thereof;

FIG. 18 is a rear elevational view thereof;

FIG. 19 is a top plan view thereof; and,

FIG. 20 is a bottom plan view thereof.

Broken lines in the drawings are for the purpose of illustrating environmental structure and form no part of the claimed design.
